UNITED STATES PATENT OFFICE.

GEORG SPIESS, OF LEIPZIG, GERMANY.

DEVICE FOR FEEDING SHEETS TO PRINTING PRESSES, FOLDING MACHINES, AND THE LIKE.

Application filed October 1, 1923. Serial No. 665,759.

To all whom it may concern:

Be it known that I, Georg SPIESS, a citizen of the German Republic, and a resident of Leipzig, Germany, have invented 5 certain new and useful Improvements in Devices for Feeding Sheets to Printing Presses, Folding Machines, and the like, of which the following is a specification.

This invention comprises improvements 10 in or relating to devices for feeding sheets to printing-presses, folding-machines and the like of the type in which a feeler or pawl on an oscillating lever which controls the raising and lowering of the feed 15 wheel is actuated by the sheet that had been fed forward, is brought into engagement with a continuously rotating driving organ such as a ratchet wheel, and in which the disengagement of the pawl and ratchet 20 wheel is effected by acceleration of the oscillating lever relatively to the driving organ.

The invention consists in the combination of an oscillating lever, adapted to be engaged 25 with a continuously rotating ratchet wheel and provided with a pawl actuated by the sheet fed-in from the staple, with a link member thus forming a combination of link-levers and connected so that the acceleration 30 of the oscillating lever is increased through the increased pressure momentum when the link levers are brought nearly into the straight or stretched position and the acceleration being limited by the 35 stretched position of the link levers. The aforesaid arrangement enables a smooth working of the driving mechanism and especially a hard stop for the limitation of the acceleration is avoided. The link-levers 40 may be so arranged that the force causing its stretching may assist the action of the rotary driving organ upon the lever system, the latter serving for the raising or lowering of the feed wheel or the link 45 levers may be so arranged in said lever system that by its stretching the raising of the feed wheel is effected.

In the aforesaid arrangement a spring 50 may be used for accelerating the engaged lever system relatively to the driving organ, whereby the action of the spring upon the lever-system is so arranged that the axial direction of the spring is changed just before the stretched position of the levers is 55 reached,

In order to obtain a smooth running and to avoid hard knocks a device may be provided for locking the lever system serving for raising and lowering the feed wheel when the link levers are in the stretched position. Furthermore a special locking device 60 may be provided for securing the oscillating lever when link-levers are in the stretched position.

The spring which serves for holding the pawl of the engaging device actuated by the sheet fed-in in readiness is secured to a non-movable support in such a manner that only on the return of the oscillating lever into its normal starting position the 70 initial tension of the spring is attained. This is important because on a strong dis-tensioning of the spring it may happen that the pawl on abutting against its stop may jump back into the teeth of the rotating ratchet and may re-engage therein, thus causing interruptions of the work, and waste of material i. e. the damage of the edges of the sheets.

Moreover the known types of sheet feeding devices do not permit the increase of speed to at least 10,000 feeds.

Three forms of construction of the sheet feeding device according to this invention are illustrated by way of example in the 85 accompanying drawings in which the Figs. 1, 3 and 5 show the three devices in the normal starting position and

Figs. 2, 4, and 6 in their working position after the pawl has been disengaged 90 from the continuously rotating ratchet wheel.

Fig. 7 shows a detail of a link-lever connection.

On the feeding table 1 is spread out the 95 pile of sheets, the feed wheel 2 is mounted in a casing of the lever 4 rotatable on the shaft 3. Rigidly connected with the lever 4 is the lever 5 the forked end of which engages the pin 6 of the bell crank lever 8 100 rotatably mounted on the shaft 7. The spring 9 acting on the lever 8 presses the feeding wheel 2 onto the pile of sheets. The roller 10 on the lever arm 8 is adapted to co-operate in known manner with the race-surface 11 of the oscillating double armed lever 13 loosely pivoted on a pin 12. Rotatable on a pin 14 on the lower arm of the lever 13, is the double armed pawl 15, the 105 lower arm of which extends into the path of 110

the sheets fed from the pile thus forming a feeler. The pawl 15 is subjected to the action of a spring 16 secured on a pin 17 fixed on the frame 24 of the machine. This 5 spring action causes the pawl 15 to rest against the pivotal pin 12 as shown in Fig. 1.

Opposite the top end of the pawl 15 is arranged the ratchet wheel 18 adapted to 10 rotate continuously upon the shaft 19. Mounted on the latter is a cam 20 co-operating with the roller 21 on the bell-crank lever 8. Connected to the oscillating lever 13 are the link-levers 22, 23, one end of which is 15 secured to the machine frame 24. A roller 25 journalled in the link-levers 22, 23 is actuated by a cam 26 on a driving shaft.

The working of the device is as follows: The sheet fed-in by the feed wheel 2 meets 20 the lower arm or feeler of the pawl 15, which latter is thus brought into engagement with the teeth of the continuously rotating ratchet wheel 18, thereby slightly tensioning the spring 16. The ratchet wheel 25 18 now moves the pawl 15 until the latter abuts against the stop pin 27 on the lever 13, which latter is then moved or oscillated, whereby the roller 10 on the bell-crank lever 8 is caused to roll along the inclined racing- 30 surface 11 of the lever 13, resulting in a rotation of the shaft 7 and consequently lifting the feed-wheel 2 by means of the pin 6 and fork 5. At the same time the link-levers 22, 23 become stretched and just before being straightened out the roller 10 passes from the inclined race-surface 11 on to the horizontal race-surface 11^a of the lever 13. On account of the sudden interruption of the resistance, the lever 13 being 40 under the action of the ratchet wheel 18, receives an acceleration caused by the weight of the link-levers 22, 23. This acceleration ceases as soon as the link-levers are in a straight line, but suffices for releasing or 45 disengaging the pawl 15 from the ratchet wheel 18 by means of the spring 16.

At this moment the parts of the device will be in the position as shown in Fig. 2. The pawl 15 has thereby become moved so 50 far that its upper end rests against the pivotal pin 12 and the spring 16 is consequently only slightly distensioned so that the pawl is prevented from snapping back. During the further working cycle, the cam 26 causes the link-levers 22, 23 to be brought into the bent 55 position and thus the oscillating lever 13 restores into its normal starting position, i. e. the lever 23 abuts against the stop 36, and after the cam 26 has left the roller 25 60 is held in this position by the spring 16. The feeding wheel 2 is lowered on to the sheet pile by the co-action of the cam 18 and the spring 9 in order to feed-in a fresh sheet.

65 In the example shown in Figs. 3 and 4,

the link-levers are combined with the lever system serving for lifting the feed wheel.

The bell-crank lever 28 rotates on the shaft 7 and is provided with the roller 21, which latter is actuated by the cam 20. In 70 this form of construction the bell crank lever 28 is positively linked by means of the member 30 to a lever 29 (which substitutes in this case the oscillating lever 13 with its race-surfaces of Figs. 1 and 2), and is provided with the pawl 15.

Lever 29 and member 30 form a bent link lever, which after the pawl 15 has been brought by the fed-in sheet into engagement with the ratchet wheel 18, becomes stretched and causes the bell crank lever 28 and its shaft 7 to rotate, and consequently causes the lifting of the feed wheel 2 by means of the pin 6 and the fork 5. The acceleration of the lever 29 80 is effected—apart from the quicker movement of the lever-system on account of the reduced or interrupted working resistance during the bringing of the link-levers from the bent into the stretched position—by a spring 31 acting between a fixed point 32 and the lower arm of the oscillating lever 29, in such a manner that shortly before the link levers 29, 30 become straight, the spring 31 is caused to reverse the direction 90 of rotation of the oscillating lever 29, that is to say, that the spring 31 acts first against the force of the ratchet wheel 18 and then in the same direction thus causing the desired acceleration. This change in the rotary movement is achieved by the axial displacement of the spring 31, so that the axis of the spring is displaced to the right of the pivotal pin 12, when the lever 29 is moved to the left (Fig. 3) and the displacement to the left is caused on moving the lever 29 to the right (Fig. 4).

In order to provide a certain play between the feed wheel 2 and the link levers 29, the link member 30 may be provided with a slot as shown in the detail of Fig. 7.

Mounted on the shaft 19 of the ratchet wheel 18 is also the cam 34, co-operating with a roller 35 on the oscillating lever 29 and serving for bringing the link-levers 29, 30 from the straight position (Fig. 4) into the normal starting position (Fig. 3).

The working of this form of construction is generally the same as in the example previously described.

After the pawl 15 has been brought into engagement by the sheet fed-in, the lever 29 is rotated thus causing a stretching of the link-levers 29, 30 and a rotation of the bell-crank lever 28 and its shaft 7, resulting in the lifting of the feed wheel 2. At the same time the axial displacement of the spring 31 to the left of the pivotal pin 12 takes place and causes the acceleration of 125 the movement of the lever 29. The pawl 130

15 has thereby become released from the teeth of the ratchet wheel 18 by the action of the leaf-spring 37. The movement of the lever 29 stops automatically as soon as 5 the straight position of the link-levers 29, 30 is attained. During the further working cycle,—by the co-action of the spring 9, the cam 20, the roller 21 on the bell crank lever 28, with the cam 34, and roller 10 35 on the oscillating lever 29,—the link-levers 29—30 are brought into the bent position and the lever system as well as the feed wheel are restored into their normal starting positions, and secured therein by 15 the tension of the spring 31 and the stop 33.

The example shown in Figs. 5 and 6 differs from the last construction only by the provision of a yielding locking device for securing the whole lever system in the 20 stretched position of the link-levers 29, 30, in which position the feed wheel 2 is lifted from the pile of sheets, and furthermore for securing the oscillating lever 29 and the link member 30 in the stretched position and in the normal starting position.

The provision of these locking devices is especially recommendable when working at high speed in order to obtain a smooth running without hard knocks. The 25 devices consist on the one hand of a locking arm 39 actuated by a spring 38 and rotatable on a pin 40 fixed on the machine frame, provided with a locking notch 41 for engaging a roller 42 on the bell crank lever 28, and on the other hand of a locking arm 44 actuated by a spring 43 and rotatable on a pin 45, provided with locking notches 46, 48, for engaging a roller 47 on the oscillating lever 29.

40 The stop 33 in Figs. 3 and 4 here becomes unnecessary.

During the working cycle the lever 29, with the link member 30 and the whole lever system are securely held in the stretched position by the engagement of the roller 42 on the bell crank lever 28 in the notch 41 of the locking arm 39 and the oscillating lever 29 is furthermore secured by the engagement of its roller 47 in the notch 48 of the locking arm 44. At the same time 45 the pawl 15 becomes released from the teeth of the ratchet wheel 18. In the same manner as described in the aforementioned forms of construction the parts may be returned into the normal starting position 50 after overcoming the spring pressure on the locking arms, and are then held in this position by the engagement of the roller 47 on the oscillating lever 29 in the notch 48 on the locking arm 44.

Having thus described the invention, what is claimed as new, is:—

1. In a sheet feeding device for printing presses, folding machines and the like of the 65 type in which the lever gear of the feeding

device co-operates with an oscillating lever controlled by the advancing sheets actuating a detector pawl in co-operation with a toothed driver or ratchet wheel and in which the disengagement of the pawl and ratchet 70 wheel is effected by acceleration of the oscillating lever relatively to the driving means, the combination with the oscillating lever having cam surfaces of different inclinations, the lesser inclined surfaces exerting a greater lifting force of link-levers in such connection that the acceleration of the oscillating lever is increased through the increased pressure momentum while acting with the lesser inclined portion in operating position on the link-levers approaching a nearly straight or stretched position, said acceleration being limited by the stretched position of the link-levers.

2. A sheet feeding device as claimed in 85 claim 1 in which the link-levers are arranged between a fixed pivotal point on the machine frame and the oscillating lever.

3. A sheet feeding device as claimed in 90 claim 1 in which the oscillating lever is connected with lever systems, serving for raising and lowering the feed wheel, by means of a link member forming link-levers, so that the stretching of its members causes the raising of the feed wheel whereby the 95 acceleration of the movement of the oscillating lever during the transition into the stretched position is assisted by a spring acting upon said lever in such a manner, that it acts at the beginning of the lever movement against the same, but shortly before attaining the stretched position is acting in the same direction with and upon the oscillating lever.

4. In a sheet feeding device, a table, a feed 100 wheel arranged thereover, a lever swingingly mounting the wheel, an oscillating lever having a race surface, a lever for rocking the first lever and having a part engaging the race surface of the oscillating lever, a detector pawl pivoted on the latter, a rotating ratchet for engaging the pawl to effect movement of the oscillating lever, and means for effecting release of the pawl from the ratchet.

5. In a sheet feeding device, a frame, a table thereon, a feed wheel swingingly mounted on the frame, a detector pawl, an oscillating lever, a rotating ratchet, said pawl being pivotally mounted on the lever for being engaged by a fed sheet for being rocked into engagement with the ratchet whereby the oscillating lever will be moved in one direction, means operable by the lever for swinging the feed wheel from the table, and means for effecting release of the pawl from the ratchet.

6. In a sheet feeding device, a frame, a table thereon, a feed wheel mounted for being elevated from and lowered to the table,

- an oscillating lever, a rotating ratchet, a detector pawl pivoted on the lever for limited swinging and adapted to be moved by a fed sheet into engagement with the ratchet
- 5 whereby the latter will act through the pawl to swing the lever in one direction to a limited extent means operable by the lever to elevate the feed wheel from the table, and means for imparting a quickened movement
- 10 toward the final limit of said movement of the lever to effect a release of the pawl from the ratchet.
7. A sheet feeding device as claimed in claim 6, in which means are provided to lock said feed wheel in the elevated position.
- 15 8. In a sheet feeding device, a frame, a table thereon a feed wheel mounted for being elevated from and lowered to the table, an oscillating lever, a rotating ratchet, a detector pawl on the lever for limited swinging and adapted to be moved by a fed sheet into engagement with the ratchet whereby the latter will act through the pawl to swing the lever in one direction to a limited extent,
- 20 means for elevating and lowering the wheel
- 25 including a link pivotally connected to the oscillating lever for toggle like movement whereby said pivotal connection will move beyond dead center to lock the feed wheel elevated and said link and lever against return movement, and means for disengaging the pawl from the ratchet.
9. A sheet feeding device as claimed in claim 8 in which the pawl disengaging means comprises a tension spring positioned between the pawl and a fixed point on the frame in such manner that it resumes its normal tension only on the return of the oscillating lever into its normal starting position, but after release of the pawl at first is under greater tension, for the purpose of preventing a jumping-back of the pawl.
- 30 35 40
- Signed at Leipzig this 16th day of August, 1923.
